US0D1088036S

(12) **United States Design Patent** (10) **Patent No.:** **US D1,088,036 S**
(45) **Date of Patent:** **** Aug. 12, 2025**

(54) **DISPLAY SCREEN OR PORTION THEREOF WITH ICON**

(71) Applicant: **Yokogawa Electric Corporation**,
Musashino (JP)

(72) Inventors: **Jasper Bryan S. Ratilla**, Singapore
(SG); **Yasunori Okazaki**, Musashino
(JP); **Kan-e Kuriyama**, Musashino (JP)

(73) Assignee: **Yokogawa Electric Corporation**,
Tokyo (JP)

(**) Term: **15 Years**

(21) Appl. No.: **29/981,520**

(22) Filed: **Dec. 31, 2024**

Related U.S. Application Data

(62) Division of application No. 35/518,680, filed on Oct. 17, 2022 (U.S. filing date under 35 U.S.C. 384), and having an international filing date of Oct. 17, 2022, now Pat. No. Des. 1,060,425.
